UNITED STATES PATENT OFFICE.

PAUL VENAIL, OF PARIS, FRANCE.

POWER LOOM FOR THE MANUFACTURE OF PILE FABRICS.

Application filed July 14, 1925, Serial No. 43,613, and in France August 4, 1924.

The present invention relates to the manufacture of pile fabrics more particularly oriental, Persian, wound and other knot-stitch carpets by means of mechanically operated carpet looms of the kind wherein warp selecting combs and tuft-yarn inserters are used for winding the tufts round the warps. The general manner of operation of such looms is as follows: The warp threads are usually arranged vertically and are as a rule divided into two lines which are crossed for passing through the weft, the foundation or ground weave thus produced being either plain or of any other suitable kind. Knot-stitchers are inserted between two consecutive weft picks whilst both lines of the warp threads are restored to the closed position and lie in one vertical plane. The warp threads are separated laterally in their common plane in certain predetermined groups by means of selectors or combs so as to provide the necessary spaces for the passage of the tuft-yarn inserters which also serve for winding round the groups of warps the tuft-yarn used for making the knot-strokes between two consecutive weft picks.

The mechanical manufacture of knot-stitch carpets by means of this known kind of power looms is very limited owing to the very complicated construction and operation of the looms, their high cost, the necessity of using very skilled and expensive labour, and the very low output which was mainly due to the fact that the working process employed was a reproduction of the manual process employed in carpet making. According to this process tuft-yarn lengths were inserted between two weft picks which were exactly sufficient for passing and knotting the stitches. This operation requires a considerable amount of manual work and causes a great loss of time which is spent in removing the tuft-yarn inserters and placing them back in the required position in the carrier or box in accordance with the required order of colours for producing the pattern or design.

The object of the present invention is to reduce the drawbacks and difficulties mentioned above by providing an improved carpet loom of the general type referred to but of simplified construction and operation. The invention reduces the amount of skilled labour required and increases the output of the loom considerably, these results being

attained chiefly by the fact that the tuft-yarn is no longer introduced and wound round the warps in the manner used in hand looms, that is to say, in lengths just sufficient for the formation of a knot-stitch, but is introduced during the weaving of a ground fabric, the tuft-yarn inserters acting for this purpose like real needles the threads of which are prepared in advance for each needle, in accordance with the knot-stitch to be produced and so as to have a length sufficient to reproduce a certain number of knot-strokes which for the total arrangement of threads corresponds to a predetermined number of identical patterns or designs. By this employment and preparation of needle threads of lengths sufficient for several knot-strokes instead of a length sufficient for one knot-stitch only, the manual labour is greatly reduced and the rapidity of production is greatly increased. Assuming for the sake of example, that the carpet of the pattern repeated on the carpet consists of p points or stitches in the transverse direction, and n points or stitches in the longitudinal direction, the whole pattern comprises n times p points or stitches and it is therefore necessary to prepare n times p tuft-yarn inserters. The inserters of each row are placed in a box or carrier which enables to insert the pile threads for simultaneously knotting the stitches of a row. After the stitches have been knotted round the warps, the needle threads of the row are cut in accordance with the length of the tuft. The inserter carriers or boxes come successively into operation and when the pattern is finished the whole series of operations is repeated by the same inserter boxes or carriers until the lengths of the needle threads are exhausted, which corresponds to a predetermined number of identical patterns or motifs.

A loom embodying the various improvements and features of the invention is shown by way of example in the accompanying dia-

grammatic drawings in which:

Fig. 1 is a side elevation of the improved loom with part of the frame removed in order to show the working parts of the loom.

Fig. 2 is a partial view drawn to a larger scale of certain parts of Fig. 1 shown in a different position.

Fig. 3 is an end view partly in section of certain parts of the loom, drawn to a larger scale.

Fig. 4 is a detail elevation partly in section of the dented comb for selecting the warps.

Figs. 5, 6 and 7 are plan views of the dented comb showing same in three different horizontal positions relatively to the warps.

Fig. 8 is a detail elevation partly in section showing the dented comb in three different vertical positions, and the means for operating the shuttle-race.

Fig. 9 shows in elevation and partly in section, the boxes containing the tuft-yarn inserters and the dented comb in the position corresponding to the commencement of the insertion of the tuft-yarns between the warps.

Fig. 10 is an end view of some of the parts shown in Fig. 9.

Fig. 11 shows in elevation and partly in section the device for cutting the finished tufts.

Fig. 12 shows in elevation and partly in section, the means for operating the table for holding the finished work and cutting the tufts.

Figs. 13 and 14 show the table in two different positions.

Figs. 15 to 22 illustrate in plan views, the successive phases of the formation of a knot-stitch that is, the insertion of the tuft-yarn 30 by a needle and the winding of the yarn round the warps.

Referring to the drawings more particularly Fig. 1, the frame of the loom comprises two lateral members 1, connected by cross members 2, 2 3, 3 and the stationary beams 4 and 5. In the frame are mounted two transverse shafts 6 and 7, which are operated independently of one another by gearing not shown, and serve for operating the various working parts of the loom. A third transverse shaft 8 is operatively connected with the shaft 7 by intermeshing gears 9 and 10 so that it rotates simultaneously with shaft 7 but in the opposite direction. The said shafts 6, 7 and 8 carry various cams and eccentrics for actuating the working parts of the loom. Shaft 6 operates the parts used for the formation of the knot-strokes, one revolution of the shaft corresponding to the movement of all the parts required for inserting the tuft-yarn and winding same round the warps. Shafts 7 and 8 operate the parts effecting the ground weave. During one revolution of these shafts, the shedding motion is actuated, the weft inserted and beaten up and the tuft-yarns are cut.

The tuft-yarn inserters 11 and the boxes or carriers 12 containing the inserters are more fully described in the applicant's French Patent No. 581,024, filed 2nd May, 1924.

The inserter boxes 12 are mounted on carriages 13 provided at their ends with projections 14 (Fig. 3) sliding in grooves of two guide members 15 arranged on both sides

of the loom and connected together by cross ties 16 so as to form a rigid frame. The guide members 15 have a length sufficient to enable the carriages 13 of the inserter boxes to move a length sufficient for fully extending the tuft-yarn threaded into the inserters 11.

Each guide member 15 is provided with two shoes or carriages 17 which are guided by means of projections 18 in grooves of guide members 19 fixed to or integral with the cross members 2 of the main frame. The two inserter boxes 12 are adapted to move towards and from one another in a direction at right angles to the plane of the warps, and they can also move simultaneously together with their guide members 15 in a direction parallel to the plane of the warps. The movement of the inserter carriers or boxes along their guides 15 is effected by two pairs of chains 20 which are attached to the carriages 13 at 21. These two pairs of chains pass over pinions 22 mounted loosely upon shafts 23 fixed to the guides 15, and pass also near the centre of the loom over pinions 24 keyed to shafts 25 and 26 rotatably mounted in bearings 27 carried by the guides 15. The shafts 25 and 26 are operatively connected by gears 28 and 29.

The shaft 25 carries in addition at one end, a fixed gear 30 which meshes with a gear 31. Upon the shaft 33 of the gear 31 is mounted gear 32 which meshes with a toothed sector 34 (Fig. 2) mounted upon a shaft 35 which is actuated by arm 36, a pull rod 37, a lever 38 (Fig. 1) pivotally mounted at 39 and carrying a roller 40 engaged by an eccentric keyed upon the shaft 6.

The movement of the two connected guides 15 in the transverse direction that is, parallel to the plane of the warps, is effected by two slide rods 41 (Fig. 3) fixed to one of the guides 15. Each slide rod 41 carries two rollers 42 which are in contact with a cam 43 mounted upon shaft 44 adapted to rotate in bearings 45 of the frame 1 and operated by means of levers 46, pull rod 47, and lever 48 pivotally mounted at 39 and provided with a roller 49 in contact with an eccentric keyed to the shaft 6. The gear 30 is made sufficiently wide so as to remain always in engagement with the gear 31 whatever the transverse position of the frame 15—16.

The device for selecting the warps is preferably combined with the slay or batten of the loom which for this purpose comprises the usual comb or reed 50 (Figs. 2 and 4) mounted in a frame 51 adapted to slide up and down in two guides 52 so that it may be lifted into the position *a* (Fig. 8) to allow the weft to be passed underneath or lowered into the position *b* (Fig. 8) for the purpose of beating up the weft, or moved into an intermediate position *c* (Fig. 8) for selecting the warps. In the position *c* the batten is slightly

below the plane in which the tuft-yarn inserters move.

The frame 51 of the batten is fixed at each end at 53 to a connecting rod 54 actuated by lever 55 pivotally mounted at 56, connecting rod 57 and lever 58 pivotally mounted at 59 and provided with a roller 60 in contact with an eccentric keyed to the shaft 6, and provided in addition with a second roller 61 in contact with an eccentric keyed to the shaft 7.

It will thus be seen that the up and down movement of the batten may be produced successively by the two control shafts 6 and 7. The rotation of the shaft 6 lifts the batten into the position *c* for selecting the warps and maintains the batten in this position. The shaft 7 lifts the batten into the position *a* (Fig. 8) in which the batten is above the coinciding windows 62 of the main frame 20 and the guide 52 through which the shuttle or other weft containing device is driven for passing the weft. The shaft 7 also lowers the batten into the position *b* for beating up the weft by the reeds of the comb 50.

Underneath the comb 50 are fixed on both sides of the frame 51 two dented selectors 63 (Fig. 4) which take the place of the usual selector combs.

The projecting portions of the two selectors 63 are staggered relatively to one another and they are placed in such a manner relatively to the reeds of the comb that the points of the dented members lie in line with alternative reeds of the combs, this being clearly shown in Figs. 5 to 7. The guides 52 are pivotally mounted at their upper ends about fixed pivots 64 and receive an oscillating movement by means of two connecting rods 65, two arms 66 keyed to an oscillating shaft 67, lever 68, pull rod 69, and lever 70 which is pivoted at 71 and carries a roller 72 in contact with an eccentric on the shaft 6. The guides 52 are guided at their lower ends by means of slots 52' engaging cross bars of the frame. By the oscillation of the comb 50, the two dented members 63 connected to the comb are alternately brought into engagement with the warps *j* whereby adjacent warps are brought close together and spaces are made between two adjacent pairs of warps for the passage of the tuft-yarn inserters. The groupings are clearly indicated in Figs. 5, 6, 7 and 10. Fig. 6 shows the groupings *d*—*e*, *f*—*g*, *h*—*i*, *j*—*k*, produced by the right hand member 63. Fig. 7 shows the groupings *d*, *e*—*f*, *g*—*h*, *i*—*j*, *k*, produced by the left hand member 63. The intervals or spaces *l* between the groups are particularly shown in Fig. 10. Fig. 5 shows the normal position of the warps in the comb before the latter has been moved into one or other selecting position.

The clamping and cutting table 73 (Fig. 12) serves for covering the finished row of stitches so as to avoid the finished tufts becoming entangled with the tuft-yarns while

making the following row of stitches. The table also serves for retaining or clamping the free ends of the tuft-yarns after the first insertion of the needles or inserters through the warps in order to prevent the yarn from slipping during the remaining part of the stitch making operation, this position of the parts being indicated in Fig. 14. The table is provided with a member 74 against which the comb of the cutting device strikes as will be hereinafter explained.

The cutting and clamping table is carried by arms 75 guided by means of elongated slots 77 on fixed pivots 76 and provided with rollers 78 in contact with an eccentric keyed to the shaft 6. The levers 75 carry in addition roller 79 engaging elongated slots 80 of levers 81 which are pivoted at 82 and carry rollers 83 actuated by an eccentric keyed to the shaft 6. The combined effect of the two eccentrics acting upon the rollers 83 and 78 is to move the clamping table successively into the positions 73'—74' and 73''—74'' shown in Figs. 13 and 14.

The cutting device is preferably constituted by bracket 84 (Fig. 11) carrying a dove-tailed guide member 85 on which the carriage 86 carrying the knife 87 slides. The bracket or frame 84 is carried at its two ends by arms 88 keyed to a shaft 89 which is operated by a pinion 90 and a rack 91 held in engagement with the pinion by a roller 92. The rack is actuated by means of a lever 93 pivoted at 76 (Fig. 1) which carries a roller 94 actuated by an eccentric of the shaft 7. The device is so timed as to hold the entire cutting device in its raised position as shown in Fig. 1 during the making of the knot-stitches, and bring the knife down against the cutting table (Fig. 11) after the knotting operation has been completed. When the cutting device is brought down, a comb 95 fixed to the bracket 84 rests against the table and prevents movement of the yarns or threads during the cutting movement of the knife. The movement of the knife from one end to the other of the row of yarns is effected by means of a cable or cord 96 which passes over guide rollers 97—98 and is wound upon a drum 99 keyed to a shaft 100. This shaft is alternately rotated in opposite directions for the purpose of cutting the threads or tuft-yarns and for returning the knife to its initial position, by means of a bevel gearing 101 102, a shaft 103 and two leather straps 104 fixed to the shaft and alternately operated by two levers 105 pivoted at 106 which carry rollers 107 actuated by corresponding cams or eccentrics of the shaft 7 (Figs. 1 and 11).

The loom further comprises a movable comb 108 (Fig. 8) which constitutes the shuttle race. It will however be understood that any other means for passing the weft may be employed. The comb occupies dur-

ing the other operations, the position shown in Figs. 1 and 2. It may be moved horizontally into the working position shown in Fig. 8, for which purpose it is mounted on two arms 109 sliding in fixed guides 110 of the frame. The comb is actuated by means of links 111 and levers 112 pivoted at 59 and carrying rollers 113 in contact with eccentrics keyed to the shaft 8.

10 In the described construction of the loom the warp is arranged vertically and is let off from a beam 114 arranged at the rear end of the loom. The warps then pass over two fixed beams 4 and 5 whilst the finished fabric 116 passes over a roller or beam 115 and is allowed to drop into the base of the loom or is taken up in any other convenient way.

15 The means for letting-off the warps, feeding the fabric, making the shed and picking the shuttle, are not shown in the drawings. They may be of any known kind and do not form part of the invention.

20 The means for changing the tuft-yarn inserters after their operation are not shown. The inserters may be changed by hand after the loom has been stopped, or they may be changed automatically by means of a suitable distributing device.

25 Various modifications and changes may be made in the means of operating the loom without departing from the spirit of the invention which consists broadly in producing simultaneously a whole row of knot-stitches by means of tuft-yarn inserters which are 30 passed forwards and backwards through selected warps and are each provided with a length of yarn sufficient for producing the repeat of the same carpet or pattern. The same yarn inserters might be utilized for feeding 35 successively a certain number of looms producing the same carpets or carpets having the same pattern, for instance, the first inserter box could after the first row of stitches has been made be passed on to a second loom for 40 producing there the first row of stitches and so on.

45 The operation of the improved loom as above described with reference to the drawings is as follows:

50 After the box 12 has been supplied with the inserters and fixed upon the right hand carriers 13, the loom is started and the shaft 6 commences to rotate. The clamping table is released and caused to cover the finished row 55 of stitches (Fig. 9). The batten with the dented selectors passes from the beating-up position *b* into the selecting position *c* and oscillates say into the position in Fig. 6. The two inserter boxes now commence moving 60 towards one another until they meet in the middle of the loom below the selector comb (Figs. 9 and 15). The inserters are then transferred from the right hand box into the left hand box and are moved by the left hand 65 carriage 13 into the position *B* (Fig. 16),

drawing the tuft-yarns through the warps. At the same time the warps are released by the selector comb so that they rub against the tuft-yarns and somewhat brake their movement as shown in Fig. 16. The guides 15 then move laterally so as to move the two inserter boxes from the position *A*—*B* into the position *A*¹—*B*¹. The selector comb then oscillates into the position shown in Fig. 7 whereby the second grouping of warps is effected. The inserter boxes then again exchange their inserters and the latter are moved into the position *A*¹ (Fig. 18). The two guides 15 again move laterally and the boxes are moved into the position *A*²—*B*² (Fig. 18). The selector comb rests now in the second position shown in Fig. 7, and the inserters are again passed through the warp as indicated in Fig. 19 and are then drawn into the position *B*² (Fig. 20). The selector 75 comb then oscillates and resumes its first position (Fig. 6). The guides then again move laterally so as to return into the position *A*—*B* and the inserters are now for the last time changed from one box to the other and 80 pass through the warps (Fig. 21) and finally move into the position *A* (Fig. 22). The comb then assumes the middle position 85 (Fig. 5).

90 After the shaft 6 has completed its rotation, it is stopped by suitable means and the shaft 7 commences its rotation, rotating with it the shaft 8.

95 The batten then rises into the position *a* (Fig. 8) the comb 108 advances into the warp which is now divided for forming the shed by means of any suitable shedding device for instance, the healds 117. The weft is then passed and is beaten up by the batten which moves into the position *b*, the comb 108 being at the same time withdrawn. Another shed is then made and the shuttle returned, whilst the cutting device descends and cuts the tufts along *n*—*n* (Fig. 22), whereupon the cutting device 105 is raised. The batten now beats up the second weft and the fabric 116 is fed forward.

110 The loom is then again in its initial position and the whole cycle of operations is repeated with the next following inserter boxes which carry the inserters provided with the 115 yarn colours required for the next row of stitches.

What I claim is:

1. A loom for the manufacture of pile fabrics, comprising a warp selecting reed, 120 tuft-inserting means for winding tuft-yarn around warp threads, said tuft-yarn inserting means being adapted to form a plurality of knots from a single length of yarn, a guide on which said reed is adapted to slide 125 towards and from the yarn-tuft inserting means, said guide being oscillatable about a pivot at one end of the guide.

2. A mechanically operated loom for the manufacture of pile fabric comprising a 130

warp selecting reed, and tuft yarn inserting means for winding tuft-yarn around warp threads, said tuft yarn inserting means being adapted to form a plurality of knots 5 from a single length of yarn, in combination with a table which covers the last finished row of stitches and serves for holding the free ends of the suspended tuft-yarns during the formation of the knot-strokes permitting the yarns or threads to be properly tightened round the warps, substantially as described.

3. A mechanically operated loom for the manufacture of pile fabric comprising a warp selecting reed, and tuft yarn inserting means for winding tuft-yarn around warp threads, said tuft yarn inserting means being adapted to form a plurality of knots 15 from a single length of yarn, in combination with a clamping table for holding the free ends of the tuft-yarns, and a knife moved along the clamping table whilst the latter still holds the free ends of the yarns, said knife being mounted upon a support adapted 20 to slide along a bar mounted on oscillating levers, the portions of the yarns leading to the inserters being held by a comb integral with or fixed to the bar carrying the knife, said comb resting upon the top of the clamping 25 table, substantially as described.

4. A loom as claimed in claim 1, in combination with a weft containing shuttle adapted to be passed through the warps by means of a guide adapted to be inserted into 35 and withdrawn from the warps, suitable openings or windows being provided for the passage of the shuttle in the frame of the loom and in the reed and its oscillating guides, substantially as described.

40 5. A mechanically operated loom for the manufacture of pile fabric comprising a warp selecting reed, and tuft yarn inserting means for winding tuft-yarn around warp threads, said tuft yarn inserting means being adapted to form a plurality of knots 45 from a single length of yarn, in combination with endless chains for reciprocating the tuft-inserting means, said chains being actuated by toothed gearing and a toothed

oscillating sector, the latter being operated 50 by an oscillating lever, and a cam for oscillating said lever.

6. A loom for the manufacture of pile fabrics comprising a warp selecting reed, 55 tuft-yarn inserting means for winding tuft-yarn around warp threads, said tuft-yarn inserting means being adapted to form a plurality of knots from a single length of yarn, means for movably supporting said reed; means for moving said reed towards 60 and from said tuft-yarn inserting means and means for oscillating said reed about a pivotal axis.

7. A loom as claimed in claim 6 in which said reed is provided with dented members 65 arranged below the reed to serve as the warp selectors.

8. A loom for the manufacture of pile fabric comprising a combined warp selecting and weft beating means, tuft yarn inserting means for winding tuft yarn around warp threads, said tuft-yarn inserting means being adapted to form a plurality of knots 70 from a single length of yarn, means for movably supporting said combined warp selecting and weft beating means and means to move said combined warp selecting and weft beating means up and down for vertically beating the weft threads and means in one vertical position of the combined warp 75 selecting and weft beating means to oscillate it on a pivotal axis to effect a selection of the warp threads.

9. A loom as claimed in claim 8, in which said combined warp selecting and weft beating means comprising a reed and dented members arranged below the reed to serve 85 as the warp selectors.

10. A loom as claimed in claim 8 in which said combined warp selecting and weft beating means comprising a reed and dented members provided at opposite sides of the reed to serve as warp selectors, said oscillating means acting to alternately bring into 90 operation said dented members. 95

In testimony whereof I affix my signature.

PAUL VENAIL.
